UNITED STATES PATENT OFFICE.

AUGUST ANDERSON, OF ST. PAUL, MINNESOTA, ASSIGNOR, BY DIRECT AND MESNE ASSIGNMENTS, TO NATIONAL AUTOMATIC CONCAVES AND TOOTH COMPANY, OF ST. PAUL, MINNESOTA, A CORPORATION OF MINNESOTA.

CONCAVES FOR THRESHER-CYLINDERS.

1,095,693.

Specification of Letters Patent.

Patented May 5, 1914.

Application filed October 13, 1913. Serial No. 794,999.

To all whom it may concern:

Be it known that I, AUGUST ANDERSON, a citizen of the United States, residing at St. Paul, in the county of Ramsey and State 5 of Minnesota, have invented certain new and useful Improvements in Concaves for Thresher-Cylinders, of which the following is a specification.

My invention relates to improvements in 10 cylinder concaves for threshers, its object being particularly to provide improved means allowing the easy and effective adjustment of the concaves to adapt the same to handling different kinds of grains.

To this end the invention consists in the 15 features of construction, combination, and arrangement of parts hereinafter described and claimed.

In the accompanying drawings forming 20 part of this specification, Figure 1 represents a side elevation of a portion of a thresher fitted with my features of improvement; Fig. 2 illustrates a cross section through the cylinder and concaves showing the operating 25 mechanism for the concaves in elevation; Fig. 3 is a detail view of the actuating slide for one of the concaves showing the supporting framework broken away; Fig. 4 is a detail view of one end of my improved 30 concaves; and Fig. 5 is a detail view, broken away, of part of the thresher framework and supported pawl and ratchet mechanism forming part of my invention.

Referring to the drawings, A represents 35 an ordinary thresher cylinder supported upon a shaft 2 journaled in the sides 3 of a thresher. The cylinder carries the usual teeth 4. Arranged below the cylinder are the concaves B, C, D and E. The concaves 40 B, C, and D are provided with teeth 5 co-operating with the cylinder teeth. The concave E is untoothed. The end concave E is slidable in a curved groove 6 in the concave supporting frame. The concave supporting frame has fulcrum support 8 at 45 the rear of the cylinder and forward of the cylinder is supported upon an eccentric 9 which fits into slots 10 in the frame 7. The eccentric 9 are supported upon a shaft 11 50 journaled in the sides of the thresher frame, one end 12 of the shaft being squared to receive an actuating handle and said shaft supporting, adjacent the squared end, a ratchet wheel 13 engaged by the pawl 14. Thus the

turning of the shaft 11 and supported eccentric, will turn the concave frame upon its fulcrum into adjusted relationship with the cylinder.

The rear untoothed concave E is connected by links 15 with the outer ends of the 60 lever arms 16 supported upon the shaft 17 journaled in the side walls of the thresher. One end 18 of the shaft 17 is squared to receive an actuating handle and supports a ratchet wheel 19 engaged by the pawl 20. 65 Thus the concave E is adjustable in the groove 6 by the turning of the shaft 17. The inside concaves C and D are similarly supported upon slides 21 and 21^a arranged in pairs, the concaves being supported upon 70 the slides through the medium of connected ears 22 and 23, respectively. The slides 21 have link connection 24 with the outer ends of the lever arms 25 supported upon the shaft 26 journaled in the sides of the thresher 75 framework. One end 27 of the shaft 26 is squared to receive an actuating handle and supports a ratchet wheel 28 which interlocks with a pawl 29. Similarly the slides 21^a are connected by links 30 with the outer ends of 80 the lever arms 31 supported upon a shaft 32 journaled in the sides of the thresher frame. One end 35 of the shaft 32 is squared to receive an actuating handle and supports a ratchet wheel 33 engaged by a pawl 34. 85

In operation, where certain grain, as wheat, is to be handled, the parts will stand in the position shown in Fig. 2 with all the concaves standing in alinement in the groove 6. Where in treating other grain as rye or oats it 90 becomes necessary to decrease the number of concaves the concave D, or both the concaves C and D may be quickly carried out of the groove 6 by the actuating of either or both of the shafts 26 and 32. The releasing of 95 any one of the pawls from the corresponding ratchet wheel will allow the associated supporting shaft to be turned by a handle applied to the squared end of the shaft to actuate the connected concave or concave supporting frame as the case may be.

Where the concave D is carried out of the groove the untoothed concave E may be moved forwardly against the concave C through the medium of the shaft 17. Similarly where both concaves C and D are removed the concave E may be moved forwardly against the concave B. The concave

B is held stationary by the lip 37. By turning the shaft 11 the concave supporting frame will be turned upon its fulcrum support through the medium of the eccentrics 5 toward and from the cylinder. It thus will be evident that I secure means by which the concave sections may be very quickly and easily removed without necessitating the stopping of the machine to allow removal.

10 I also provide a very simple and easy actuating concave supporting frame.

I claim as my invention:

1. In combination with a thresher cylinder, a plurality of concaves supported adjacent said cylinder, means for sliding one of said concaves out of alinement with the remaining concaves, and means for sliding one of the remaining concaves into the gap left by the removed concave.
- 15 2. In combination with a thresher cylinder, a concave supporting frame fulcrumed adjacent said cylinder, means for adjusting

said frame upon its fulcrum toward and from the cylinder, a plurality of concaves slidably supported upon said frame adjacent 25 said cylinder, means for carrying one of said concaves out of alinement with the remaining concaves, and means for removing one of the remaining concaves into the gap left by the removed concave.

3. In combination with a thresher cylinder, a plurality of concaves slidably supported in alinement adjacent to said cylinder, means for independently carrying the central concaves out of alinement with the 35 main concaves, and means for sliding one of the remaining concaves into the gap left by the removed concaves.

In testimony whereof I affix my signature in presence of two witnesses.

AUGUST ANDERSON.
